D7-339

EX
OR D 5,558

No. 8-3-8-8,

Feb. 27. 1872.

UNITED STATES PATENT OFFICE.

CHARLES H. BUCK AND WILEY S. WRIGHT, OF ST. LOUIS, MISSOURI.

DESIGN FOR A COOKING-STOVE.

Specification forming part of Design No. 5,558, dated February 27, 1872.

To all whom it may concern:

Be it known that we, CHARLES H. BUCK and WILEY S. WRIGHT, of St. Louis, in the county of St. Louis and State of Missouri, have produced a new and original Design for a Cook-Stove; and we do hereby declare that the following is a specification:

The nature of our design is fully represented in the accompanying photographic illustration, which is a perspective view, showing the front and one side of the stove.

Above the two doors at the front of the stove, and upon the door of the opening which leads into the fire-chamber, the letters B & W are seen surrounded by a molding. In the center of each one of the two lower doors at the side

of the stove is seen a rosette in relief, which is surrounded by a molding. The upper door on the side of the stove has an ornamental letter G in its center, which is surrounded by a molding corresponding to the molding of the doors below. Any other ornamental letter may be formed on the small upper door. The vertical corners of the stove represent pillars.

We claim—

The design for a cook-stove, as represented and described.

CHARLES H. BUCK.
WILEY S. WRIGHT.
